4 Claims. (Cl. 153—34)

1

This invention relates to improvements in bending tools for use in presses, that is to say, tools for bending tubes or rods of circular or other cross section from straight lengths into curved form.

Tools are already known which serve to bend a straight length of tube or rod by pressure between two die members which define the shape of the bend required. In U. S. Patent No. 2,369,486 issued Feb. 13, 1945, a tool is described in which the bending of the tube takes place by relative movement between the tube and a shaping die of gradually increasing curvature which ultimately defines the shape to be imparted to the tube. Also, in U. S. Patent No. 2,357,605 issued Sept. 5, 1944, there is described a tool in which the tube after being first brought to a shape in one plane by either of the above kinds of tool is brought to a shape in another plane by a shaping member moving relatively to the shaping means first employed for example between two die members.

In all the tools briefly referred to above there is a limit to the extent of curvature which can be imparted to a tube or rod and the object of the present invention is to provide a tool for forming pronounced bends in rods or tubes. A further object of the invention is to provide a double acting tool so that at least two bends of similar or dissimilar curvature lying in the one plane may be formed at the one time by a single operation of the press in which the tool is located.

The tool according to the present invention consists of a bed on which is located a form block adjacent which are at least two guide-ways at an angle to one another and each having a slideable thrust element adapted to be moved by a cam member movable relatively to such bed whereby a tube or rod located adjacent the form block is forced to take the shape defined thereby initially by the one slideable thrust member and finally by the second or another slideable thrust member on causing movement of the cam members relatively to the bed.

According to a further feature of the invention the form block has a pair of shape defining surfaces or there are two form blocks, and two slideable thrust elements each in a guide-way are provided for each shaping surface or each form block. This form of device may be arranged to bend the rod or tube into C or closed C form or into S form and shapes similar to these letters.

The two cam members or the two (or more) pairs of cam members as the case may be are

2

secured to a bridge piece so that they are caused to move together relatively to the bed, and the cam members are so shaped and their commencement displaced linearly that the one slideable thrust member is moved from its initial position to its opposite limit position before the complementary slideable thrust member commences to move. Where there are two pairs of slideable thrust members and associated cam members, the various cams may operate sequentially or in pairs one after the other as may be appropriate for imparting a desired bend to a tube. In all cases the cam members are arranged to enter in slots in the bed, the mouths of which slots serve as the guide-ways for the slideable thrust members. The cam members may be guided by the provision of guides which may be separately arranged to guide them and the bridge member as a whole or individually as by the provision of rails or similar projections which act in recesses in the slots in the bed through which the cam members pass.

The tool as a whole is conveniently made of wood but if desired the slots in the bed may be metal faced or faced with tough fibre in order to avoid wear. The working surfaces of the cam members as well as the faces of the slideable thrust members may also be fibre faced, although the latter may be made entirely of tough fibrous material.

In order that the invention may be clearly understood and readily carried into effect, embodiments of tools in accordance with the invention are by way of example hereinafter more fully described with reference to the accompanying drawings which are given for purposes of illustration only and not of limitation.

In these drawings:

40 Figure 1 is a perspective view of a tool for forming a single bend to a rod or tube with the parts thereof shown in the position they occupy prior to use.

45 Figure 2 is a view similar to Figure 1 showing the positions of parts of the tool at the completion of the first stage of its operation.

Figure 3 is again a similar view to Figure 1 showing the positions of the parts of the tool at the completion of the second stage of its operation.

50 Figure 4 is an under plan view of the tool of Figure 1, and

Figure 5 is a section taken on the line V—V of Figure 4 shown on a somewhat larger scale.

55 Figure 6 is a perspective view of the movable

cam member of a tool for imparting two bends to a rod or tube against a single form block,

Figure 7 is a plan view looking on the table of a tool for imparting two bends to a rod or tube against a single form block with the parts shown in their initial position.

Figure 8 is a view similar to Figure 7 with the parts shown at the completion of the first stage of operation.

Figure 9 is again a view similar to Figure 7 showing the parts at the completion of the second stage of operations, and

Figure 10 is a plan view of the table of a tool for imparting two bends to a rod or tube against two form blocks.

Referring now to the said drawings and in particular to Figures 1 to 5 thereof, the tool comprises a bed 1 which is supported on a plurality of legs 2 at a distance above the bed of the press in which the tool is to be used. On the surface of the bed 1 there is located a form block 3 adjacent which are T-shaped slots 4, 5 which extend through the bed and have their axes at an angle to one another, for example at right angles as shown in the drawings. The shank portions of each of the T-shaped slots 4 and 5 are faced with strips of wear-resisting tough fibrous material 4¹, 4¹¹ and 5¹, 5¹¹ respectively. A slidable thrust member 6, 7, which is conveniently of tough fibre material and is of substantially H shape seen end on (see Figure 5), is arranged in the respective slots 4, 5 to ride along the wear-resisting portions 4¹, 4¹¹ and 5¹, 5¹¹ respectively. Each slidable thrust member 6, 7 engages a guide member and is drawn to the end of its respective slot furthest from the form block conveniently by means of a pair of springs 8, 8¹, the ends of which are attached to a cross bar 9 on the under side of a slidable thrust member and to blocks 10, 10¹ on the under side of the bed 1 (see Figure 4), after the final operation, as will be hereinafter more fully described.

The co-operating relatively movable portion of the tool consists of a bridge piece 11 from which depend guide members 12, 13 which enter the transverse portions of the T-shaped slots 5 and 4 respectively. Extending at right angles to the guide member 13 is a cam member 14 having a sloping portion 14¹ and a plain sided portion 14¹¹. A similar cam member 15 extends at right angles to the guide member 13 and this cam member also has an inclined surface 15¹. The arrangement is such that as the bridge piece is moved by the ram of a press towards the bed 1 it is guided by the guide members 12, 13 working in their slots in the bed 1 and the cam members 14, 15 enter the shank portions of the slots 4, 5 so that their inclined surfaces 14¹, 15¹ engage and displace the slidable thrust members 6, 7 to move them along the slots in which they are located. The cam member 14 is longer than the cam member 15 and the arrangement is such that during the first stage of movement, the slidable thrust member 6 is first moved along its slot 4 by the inclined surface 14¹ of the cam 14 and thereafter held in that limit position by the plain edge 14¹¹. After the completion of this initial operation, the sloping surface 15¹ of the cam member 15 engages the slidable thrust member 7 and causes it to move along its slot 5 also until it reaches its opposite limit position, at which time the bridge piece 11 has been moved its maximum distance towards the bed 1, limited for example by the block 16 engaging the surface of the bed. The lengths of the legs 2 are such that the guide

members 12 and 13 may pass through the bed 1 to maximum possible extent without contacting the bed of the press. To restore the bridge piece 11 and the parts carried thereby to initial position, a depending rod carried by the bridge piece 11 extends through a sleeve 17 mounted on the bed 1 and a spring 18 is disposed around this rod such that the spring is compressed during movement of the bridge piece 11 towards the bed 1 and the energy stored by this spring returns the bridge piece automatically to its initial position on raising the arm of the press. The slidable thrust members 6, 7 are automatically returned to their initial positions by the springs 8, 8¹ and, after removing the bent rod or tube, the tool is ready for further use.

In using this form of tool a tube 19 is located against the form block 3, for example by engaging in a recess therein where a short tube is in position as shown in Figures 1 to 3. On completion of the initial stage of operation (see Figure 2) the slidable thrust member 6 by pushing on the tube 19 has caused it to bend round to a curvature determined by the form block with the end of the tube passed across and in front of the slidable thrust member 7 so that when that thrust member is moved it further displaces the end of the tube and causes it finally to take the shape defined by the complete form block 3 as may be seen in Figure 3. The bent tube is substantially C-shape.

Referring now to Figures 6 to 9 of the drawings, the general arrangement of the tool for imparting two bends to a rod or tube here illustrated is similar to the single bend tool already described and as previously comprises a bed 21, similarly supported on a plurality of legs, on the surface of which bed is provided a form block 23 having an opposed pair of shaping surfaces 23¹, 23¹¹. Adjacent the shaping surface 23¹ is a pair of angularly disposed slots 24, 25 in which act slidable thrust members 26, 27 respectively. Adjacent the other shaping surface 23¹¹ is another pair of angularly disposed slots 28, 29 in which act slidable thrust members 30, 31. A block 32 is placed adjacent the form block 23 to provide a channel in which a tube 33 may be located. The position for the end or ends of the tube may be determined by location blocks 34, 35. The relatively movable part (Figure 6) of this tool similarly comprises a bridge 36 which in this case has four depending guide members 37, 38, 39, 40 carrying cam members 41, 42, 43 and 44 respectively. The cam members 41, 43 are of similar shape and extent whilst the cam members 42, 44 are also of similar shape and extent. The cam members 41, 42 act in the slots 25, 24 respectively whilst the cam members 43, 44 act in the slots 29, 28 respectively. During initial movement of the bridge piece 36, the cams 42, 44 due to their sloping surfaces 42¹, 44¹ move the slidable thrust members 26, 30 so that they simultaneously partially bend the tube 33 around the shaping surfaces 23¹, 23¹¹. After completion of the movement of the thrust members 26, 30 (see Figure 8) the ends of the tube 33 pass beyond and in front of the thrust members 27, 31 which are next moved simultaneously by the inclined surface 41¹ of the cam member 41 and the inclined surface 43¹ of the cam member 43 respectively, further to bend the tube 33 and bring it to the shape defined by the form block 23 when the tube has a closed C-shape as may be seen from Figure 9.

In Figure 10 is shown a modification of the tool

illustrated in Figures 7 to 9 in which there are two form blocks 60, 53 disposed side by side to leave a channel to accommodate a tube 33, the ends of which tube are located as in the previous example by blocks 34, 35. Adjacent the shaping surface 60¹ of the form block 60 are a pair of slots 45, 46 similar to the pair of slots 24, 25 and adjacent the shaping surface 53¹ of the form block 53 is another pair of slots 47, 48 also similar to the slots 24, 25 but displaced 180° with respect to the other pair of slots. In this case the cam members effective on the thrust members 49, 50 in the slots 45, 47 are of similar shape and extent and by their movement bend the tube 33 in opposite directions about the respective form blocks 60, 53 substantially similar amounts. The thrust members 51, 52 in the slots 46, 48 are next brought into operation by cam members which are also of similar shape and extent, similar to the cam members 42, 44 to complete the bending of the tube to the shape defined by the form blocks 60, 53 so that the resultant tube is substantially S-shaped.

The shaping surfaces 23¹, 23¹¹ may be of different curvature or the surfaces of the two form blocks 60, 53 may be differently curved when the timing of the coming into operation of the cam members may be altered so that the thrust members move at different times, for example one after the other, thus the shaping of one end of a tube may be complete before the shaping of the other end, or one end of the tube may be partially bent at the time the bending of the other end thereof starts.

In the bending of a tube by tools such as described above, the tubes are filled with any convenient filler known in the art, such as sand, resin, or a low temperature melting point alloy. Such fillers virtually make the tube into a solid rod, and wherever a tube is mentioned herein that term is intended to include the alternative, namely a solid rod or bar.

I claim:

1. A tool for bending tubes and rods including a base board, a form block having a shaping surface mounted on said base board, at least two angularly disposed slots in said base board adjacent the shaping surface of said form block, a thrust member slideable in each of the slots, means to hold part of an elongated tube or rod to be bent on said base board in contact with said form block with another part of said tube or rod projecting into the path of one of said thrust members, and means acting through said slots for moving said thrust members along their slots in succession whereby said thrust member into the path of which the tube or rod projects moves first to effect a partial bending so as to bring a third part of the tube or rod into the path of the other thrust member which subsequently completes the bending operation in the same direction.

2. A tool for bending tubes and rods, including a base, a form block having a pair of opposed shaping surfaces on said base, a separate pair of angularly disposed slots in said base adjacent each of the shaping surfaces of said form block, pairs of thrust members slideable in said pairs of slots, respectively, means to hold the central portion of an elongated tube or rod on said base in a fixed position in which portions of said tube or rod adjacent said center portion are in contact with corresponding points of said two shaping surfaces, respectively, with the outer portions of

the tube or rod projecting into the paths of one of the thrust members of each pair, respectively, and means acting through said slots for moving the thrust members of each pair along their slots in a predetermined succession, whereby said first mentioned thrust members, into the paths of which the outer portions of the tube or rod project, move simultaneously in substantially the same direction to effect a partial bending so as to bring the ends of the tube or rod into the paths of the other thrust members of the corresponding pairs which subsequently move towards each other to complete the bending operation.

3. A tool for bending tubes and rods, including a platform supported above the bed of a press, a shape defining member mounted on the upper surface of said platform, at least one pair of angularly displaced slots in said platform extending away from said shape defining member, a thrust member slideable in each of said slots, transverse enlargements to each of said slots, a bridge member movable by the ram of the press towards said platform, guide members attached to said bridge member and each acting in the enlargement of one of said slots, and a cam member mounted fast with each guide member and engaging a thrust member to move it along its slot.

4. A tool for bending tubes and rods including a base having its upper surface spaced above the bed of a press, at least one form block having a shape defining surface mounted on said upper surface, a pair of angularly displaced slots in said upper surface extending away from each shaping surface, a thrust member in each of said slots, spring means urging said thrust members towards the ends of their slots remote from said shaping surface, transverse enlargements at the remote ends of each of said slots, a bridge member movable by the ram of the press towards the upper surface of said base, spring means tending to move said bridge member away from said upper surface, guide members attached to said bridge member and each acting in an enlargement of one of said slots, and a cam member having an inclined working surface fast with each guide member in relative linear displacement to bring their inclined surface into operative engagement with a thrust member in predetermined order.

GEORGE GREENWOOD.
